Fig. 5

Fig. 6

Fig. 7

FIG. 1 is a perspective view of a transmission embodying my new design, with the shift member broken away to indicate indeterminate length;

FIG. 2 is a front elevation thereof, the broken line showing of the shift knob has been omitted for convenience of illustration;

FIG. 3 is a top plan view thereof;

FIG. 4 is a bottom plan view thereof;

FIG. 5 is a left side elevation thereof;

FIG. 6 is a right side elevation thereof; and

FIG. 7 is a rear elevation.

The dominant features of my design reside in those portions shown in full lines.

I claim:

The ornamental design for a transmission, substantially as shown and described.
